LAMP FIXTURE

Julian A. McDermott, 1639 Stephen St., New York, N.Y.
Filed Dec. 4, 1962, Ser. No. 242,142
5 Claims. (Cl. 240—151)

This invention relates broadly to lighting fixtures, and more specifically to directional type lighting fixtures. Directional lamps are frequently used as warning lamps. A directional lamp must be so constructed, that easy access to its interior can be had, when it is necessary to replace burned-out bulbs.

Barrel type or cylindrical type fixtures are frequently preferred as warning lamps, since they are simple and rugged in construction. Difficulty arises when a bulb must be replaced. The lens must be pried out of the cylinder, resulting in loss of time and possible damage to the lens. If the bulb is maintained on the outside edge of the cylinder, it is subject to damage and tampering. If the lens is maintained in the frame in a sufficiently loose position so that the lens can be caused to fall out by itself, urging means will not be required, but in such construction, the entire fixture must be tipped to effect the release of the lens, which is not practical when the fixture is mounted on a stanchion or other support.

With this in view, it is the principal object of the present invention to provide a lighting fixture of this character, wherein a lens is maintained in the cylinder by tamper-resistant means.

Another advantage of the present invention resides in the provision of an axially rotatable arm, the rotative movement of which will tip a part of the lens out of the cylinder into a position where it can be manually withdrawn from the cylinder.

A still further aim of the present invention resides in the provision of a lighting fixture of this character having tamper-resistant retaining means for the lens which are adapted to be removed from the path of the lens when it is desired to remove or re-insert the lens.

A still further purpose of the present invention resides in the provision of means whereby the lens removal and replacement can be accomplished with a minimum loss of time and without special tools.

These and other meritorious aims and advantages which will become more fully apparent as the description hereof proceeds, are attained by the novel construction, combination and arrangement of parts, hereinafter described, and illustrated in the accompanying drawing, constituting a material component of the present disclosure, and in which:

FIGURE 1 is a top plan view of the principal embodiment of the present invention.

FIGURE 2 is a partial plan view of the embodiment illustrated in FIGURE 1, one lens being illustrated in the process of ejection from the cylinder.

FIGURE 3 is a front elevational view of the lighting fixture illustrated in FIGURE 1, part of one lens being broken away to show the interior construction.

FIGURE 4 is a side elevational view partly in section of the lighting fixture illustrated in FIGURE 3.

FIGURE 5 is a bottom view of the lighting fixture illustrated in FIGURE 3.

FIGURE 6 is a fragmentary view of the upper segment of a lighting fixture showing a modified form of a lens ejecting arm.

FIGURE 7 is a view similar to FIGURE 6 showing another modified ejecting arm.

FIGURE 8 shows the modified arm illustrated in FIGURE 7 in the process of ejecting a lens.

Referring in greater detail to the drawing, and more particularly to FIGURES 1 through 5 thereof, the nu-

2

meral 10 illustrates in general a cylinder type lighting fixture provided with a lens ejecting arm construction in accordance with the principal embodiment of the present invention. Lighting fixture 10 comprises broadly a stand 11 which may be constructed in any suitable and desirable manner. Mounted upon and secured to the stand 11 is a ring-like frame member 12 in which are spacedly retained a pair of lenses 13. The use of two lenses is optional, since some lighting fixtures of this character have only one lens. Secured to stand 11 and positioned between lenses 13 in any suitable and desirable manner is a bulb and a bulb retaining mount 14 of conventional construction.

At spaced intervals, frame 12 is provided with a plurality of stop pins 15 and 15a, three such pins being illustrated in the drawing, the purpose of which it is to retain the lens or lenses firmly in the said frame member, the specific purpose of pin 15a being to prevent the lens from becoming inadvertently disengaged at the bottom of the frame member. A removable bolt 16 is provided to retain each lens in position in the frame 12.

All of the elements hereabove described are conventional and do not constitute a part of the present invention.

25 The present invention comprises a lens ejection arm 17, secured by welding or otherwise to a bolt 18a terminating at one end in a screw head 18, the said bolt 18a extending into frame 12 between lenses 13 as is illustrated in FIGURE 3 of the drawing.

30 Between the screw head 18 and the frame 12, an eccentric washer 19 is secured to bolt 18a for a purpose which will presently become more fully apparent. Adjacent eccentric washer 19, the said frame member 12 is provided with a stop rivet 19a, the purpose of which will also presently become more fully apparent. A rubber gasket 21 may be circumferentially provided for each of the said lenses 13 to prevent water from entering the interior of the lighting fixture.

Reference numeral 20 designates a conventional base 40 for conventional lamp mount 14 through which electric wires 22a pass through stand 11 in a conventional manner.

The modification illustrated in FIGURE 6 comprises an ejection arm 17a terminating at one end in a hook and its other end in a screw head 18a, the said hooked end positioned in frame member 12a between lenses 13. Retainer screws 16a are provided, one for each of the said lenses 13a. Water-proof gasketing 21a may be provided for each of the said lenses. The head of a conventional screw 50 driver 17b is shown in engagement in screw head 18a.

The modification illustrated in FIGURES 7 and 8 comprises a substantially V-shaped ejecting arm, one leg 17b of which is positioned in frame member 12b in contact with lens 13b. The other leg 17b of which extends outwardly through an opening in the said frame 12b and in its inoperative position the underside 18c of the said leg 17b rests upon frame member 12b. Leg 17b, near the upper end thereof, is provided with a stop member 18d for a purpose which will become apparent presently. Adjacent the ejection arm 17, the outer face of frame member 12 may have a two-directional arrow 27 provided thereon by painting or otherwise.

The device is used in the following manner:

When it is desired to remove a lens in order to replace a bulb or for any other reason, screw 16, which retains the lens in the frame member, is withdrawn as illustrated at 16a in FIGURE 6. By using a conventional screw driver in an obvious manner, the arm 17 is urged against lens 13 as illustrated in FIGURE 2, until the lens is sufficiently ejected to permit the user to enter a finger behind the lens and withdraw the partly ejected lens

manually. Rotation of arm 17 is limited by the provision of the eccentric washer 19 which will be stopped on contact by pin 19a. This has the advantage, when double lenses are used, that the ejection arm is always on the side indicated by arrow 27, so that the user will know the direction in which to turn the screw head 18. When the lens is ejected, pin 15a will prevent the lens from dropping out of the frame. It must be manually withdrawn, thus reducing the danger of breakage. When desired, the removed lens is returned to its position in the frame in an obvious manner. Toward that end, the purpose of pins 15 is to position the lens and prevent it from being entered too far into the frame. Screw 16 is returned into position and the lighting fixture is again ready for use.

Ejection arm 17a differs from ejection arm 17 in that the former is hooked and therefore need not be provided with an eccentric washer, so that it can rotate axially without stop.

The modification illustrated in FIGURES 7 and 8 differs from the other forms in that the ejection arm 17b rotates in a vertical plane instead of a horizontal plane. Thus, by lifting the leg 18b, ejection of lens 13b is accomplished, as is illustrated in FIGURE 8 of the drawing.

Thus there has been shown and described a lighting fixture having a cylindrical frame, and the best known ways of ejecting a lens from the frame. It is to be understood that the present disclosure is to be regarded as illustrative and descriptive of the best known forms of the present invention and not as limitative or restrictive to the exact details shown, applicant reserving the right to make such changes in the construction of his invention as might come within the scope of the appended claims without thereby departing either from the spirit or the scope of the present invention.

Having thus described the invention, what is claimed as new and desired to secure by Letters Patent, is:

1. The combination with a cylindrically shaped lighting fixture including a frame having a pair of spaced-apart lenses removably retained therein; of a device for selectively tipping a segment of a lens edge out of the frame to a position where the tipped lens can be manually withdrawn from the frame, said lens tipping device comprising a body member, said body member rotatably mounted in the frame, one end of said body member extending through and into the frame to a position between the lenses, means on said end tipping the lens upon contact, and said lens tipping means operable from outside the frame.

2. The combination with a barrel type lighting fixture including a frame having a lens removably retained therein; of means for tipping a segment of the lens edge out of the frame into a position where it can be manually withdrawn from the frame, said lens tipping means comprising a stem, said stem axially rotatably mounted in the frame, one end of said stem entered into and

5 through the frame to a position adjacent the lens, lens tipping means on said stem end to tip a segment of the lens out of the frame upon impact of said lens tipping means with the lens edge, and said impact producing means activated from outside the frame.

3. The combination with a cylindrically shaped warning lamp including a frame member edgewise retaining a pair of spaced-apart lenses therein; of a device for tipping selectively a segment of a lens edge out of the frame into a position where the tipped lens can be manually withdrawn from the frame, said tipping device comprising a stem, said stem axially rotatable in the frame, one end of said stem entered into and through the frame to a position between the lenses, a hook formed at said stem end in alignment with a lens edge, forceful contact of said hook with the lens tipping the lens edge out of the frame, and said contact producing means operable from outside the frame.

4. The combination with a cylindrical warning lamp including a frame having a pair of spaced-apart lenses retained therein edgewise; of a device to tip a segment of either lens out of the frame to a position where the tipped lens can be manually withdrawn from the frame, said lens tipping device comprising a stem axially rotatable in the frame, one end of said stem extending into and through the frame to a position between the lenses, a hook formed integrally with said stem end, forceable contact of said hook with either of the lenses tipping the lens segment out of the frame, the other end of said stem terminating in a screw head, and said screw head adapted to be turned to activate the hook of said stem.

5. The combination with a warning lamp of the character described; of means to tip a segment of the lens edge out of the frame, said tipping means comprising an axially rotatable stem in the frame, one end of said stem entered into and through the frame into a position between the lenses, a hook formed integrally with said stem end, forceable contact of said hook with a segment of a lens tipping the lens segment out of the frame, the other end of said stem terminating in a screw head, rotation of said screw head outside the frame causing contact between said hook and the lens segment, an eccentric interposed between said screw head and the frame, and a stop on the frame in the path of the eccentric limiting the rotative movement of said stem.
